DESCRIPTIONFIG. 1 is an upper front perspective view of a hatclip
according to the present invention.

FIG. 2 is a top plan view of the hatclip of FIG. 1.

FIG. 3 is a front elevational view of the hatclip of FIG. 1.

FIG. 4 is a rear elevational view of the hatclip of FIG. 1.

FIG. 5 is a bottom plan view of the hatclip of FIG. 1.

FIG. 6 is a left side elevational view of the hatclip of FIG.
1.FIG. 7 is a right side elevational view of the hatclip of FIG.
1; andFIG. 8 is an upper front perspective view of a hatclip
according to the present invention.FIG. 9 is a front elevational view of the hatclip of FIGS. 1
and 8.FIG. 10 is a rear elevational view of the hatclip of FIGS. 1
and 8.FIG. 11 is a left side elevational view of the hatclip of FIGS.
1 and 8; and,FIG. 12 is a right side elevational view of the hatclip of
FIGS. 1 and 8.The broken line portions of the disclosure are for illustrative
purposes only and form no part of the claimed design.**1 Claim, 5 Drawing Sheets****US D550,549 S**
